UNITED STATES PATENT OFFICE.

LEE J. BLACK, OF BEAUMONT, TEXAS.

HYDRAULIC ROTARY CORE-TAKING DEVICE.

Application filed December 3, 1923. Serial No. 678,204.

To all whom it may concern:

Be it known that I, LEE J. BLACK, a citizen of the United States, residing at Beaumont, in the county of Jefferson and State of Texas, have invented certain new and useful Improvements in Hydraulic Rotary Core-Taking Devices, of which the following is a specification, reference being had therein to the accompanying drawing.

10 This invention relates broadly to that class of invention known as earth boring. But it has more particular reference to what may be conveniently termed a hydraulic rotary core taking device and drill for oil wells, the same being analogous to that class of similar devices employed to simultaneously pierce the earth and collect a sample or core of the various formations of strata being penetrated.

15

20 The prime feature of the present invention is that it is a decided improvement on prior devices of the same class due to the fact that it is more dependable, practical, and of such construction that an accurate 25 and complete incohesive sample or core of the formation of the various strata is certain to be obtained when the device is extracted and brought to the surface.

20 More specifically speaking, another feature of the invention is the novel core taking device which is equipped with rotary disk-cutters so that more or less obstinate strata may be pierced to obtain samples such as cannot be obtained with the well known fish-tail bits such as are commonly employed in association with prior devices of this class.

Another feature and outstanding advantage of the invention is the improved method and structure for facilitating entrance and collection of the core, which result is insured by the provision of a passage in the body which is restricted in diameter at its entrance, but is of a sufficient diameter 40 above this restricted entrance to prevent clogging as the core is pushed upwardly.

50 I also aim to improve upon devices of this class by preventing possible loss of the core during the period of extraction, this result being obtained by a double valve arrangement in the core receiving tube, one valve serving to prevent fluid from entering the tube at the top and the other valve being normally open to permit passage of 55 the core thereby, but automatically closing as soon as the device is elevated.

Numerous other features and advantages of the invention will become evident as the description goes on.

In the accompanying drawings forming 60 a part of this specification and in which like numerals are employed to designate like parts throughout the same:—

Fig. 1 is a side elevation of the drill body.

Figure 2 is a bottom plan view of said 65 body.

Figure 3 is a top plan view thereof.

Figure 4 is a central vertical sectional view taken on the line 4—4 of Fig. 1, looking 70 in the direction of the arrows.

Figure 5 is a horizontal section taken on the line 5—5 of Figure 4.

Figure 6 is an assembled view of the complete device with portions in section and 75 elevation.

Figure 7 is a fragmentary view of the upper portion of Figure 4, showing the valves in open position.

Referring now to the drawings in detail, 80 we will observe that the invention comprises a body 1, having a relatively large upper portion provided with a tapered screw-threaded part 2. Depending from the upper portion is a relatively small tubular part constituting a barrel 3, and detachably 85 connected with the lower end of this barrel is an extension 4. The upper portion of the body is bored longitudinally and this bore is aligned with the bore of the barrel extension. In this connection, I wish to 90 point out, as before indicated, that the diameter of the bore of said extension is slightly smaller than that of the bore above it to facilitate entrance and upward passage of the core. Thus, clogging is prevented. It may also be logically set forth here 95 that the body is provided on substantially diametrically opposite sides with integral tangentially disposed ribs 5, the lower portions of which are bifurcated to provide 100 mounting means for a pair of disk-cutters 6. For the purpose of furnishing the bearings with lubrication, a pair of small passages 7, extend thru the body and lead to the bearings. The body is also equipped 105 with two or more larger vertical passages 8 thru which the drilling circulation or mud laden fluids pass.

110 Directing attention to the upper portion of the body, it will be seen that the same is counterbored as indicated at 9, this counterbore being screw-threaded to permit a cy-

2
cylindrical member, hereinafter referred to as a valve housing 10, to be tapped into it. The upper end of the housing extends beyond the body and is internally screw-threaded for a purpose to appear later. The opposite or lower end of the housing is counterbored as at 11 to accommodate a pair of opposed pivoted flap-valves 12. As seen more clearly in Fig. 7 these valves are substantially semi-circular in cross section so that when they are swung upwardly to inoperative position they will lie in close proximity to the wall of the counterbore, thus rendering their inner faces substantially flush with the wall of the main bore or core passage. Hence, a perfectly cylindrical core may be formed due to this construction. However, as soon as the device is extracted, these valves close quickly and entrap the core in the receiving tube 13 which is threaded into the upper end of the part 10.

For the purpose of preventing fluid from entering the tube just described and destroying the natural condition of the core in its formation, I place a suitable valve 14 on the upper end of the tube. Furthermore, in order to impart rotation to the device, I connect a casing 15 to the upper threaded end 2 of the aforesaid body, sufficient space being left between the casing and the tube to permit free circulation of the mud laden fluids. The casing, of course, constitutes the usual drill stem.

In practice, the device is set into rotation in the usual way by conventional driving means and the cutting disks cause it to penetrate the earth. Obviously, as the device passes downwardly, a sample of the formation being pierced enters and is retained in the receiving tube. As the intake of the device is specially constructed, the core enters freely in its natural state and is trapped by the valves, and when the tool is extracted, an accurate and incohesive sample is had for analyzing above the sur-

face. The rotating disk cutters insure proper descent of the tool. Hence, it is evident that I have evolved and produced an extremely practical and very novel device for simultaneously drilling and taking a core.

While I have shown the relative proportions of the several details of the device, I wish it to be known that such showing is not to be regarded as controlling, for they may be varied within the scope of the claims to meet any and all requirements.

I claim:—

1. A device of the class described comprising a body having a longitudinal bore extending therethrough, the upper end of which is increased in diameter and screw-threaded, ribs on opposite sides of the body extending tangentially therefrom in opposite directions, rotary disk-cutters carried by said ribs, the lower portion of said body being reduced in diameter and being equipped with a renewable extension disposed beyond the peripheries of said cutters, a valve housing fitted into the enlarged upper portion of said bore, and a pair of flap-valves pivoted in the housing.

2. A device of the class described comprising a body having a longitudinal bore extending therethrough, the upper end of which is increased in diameter and screw-threaded, ribs on opposite sides of the body extending tangentially therefrom in opposite directions, rotary disk cutters carried by said ribs, the lower portion of said body being equipped with a renewable extension disposed beyond the peripheries of said cutters and being reduced in diameter, a valve housing fitted into the enlarged upper portion of said bore, valves pivoted in said housing, and valved core collecting and retaining means attached to said housing.

In testimony whereof I hereunto affix my signature.

LEE J. BLACK.
